COMBINED MOTORCYCLE CARRIER TRUNK AND BACK REST

Roy D. Mattson and Ross B. Mattson, Lake Elmo, Minn.,
assignors to Accessory Research Engineering, St. Paul,
Minn.

Filed Mar. 24, 1975, Ser. No. 561,334

Term of patent 14 years

Int. Cl. D12—11

U.S. Cl. D12—158

FIG. 1 is a perspective view of a combined motorcycle carrier trunk and back rest showing our new design;

FIG. 2 is a right side elevation view thereof, the left side being a mirror image of the right side shown herein;

FIG. 3 is a front elevation view thereof;

FIG. 4 is a rear elevation view thereof;

FIG. 5 is a top plan view thereof; and

FIG. 6 is a bottom plan view thereof.

We claim:

The ornamental design for a combined motorcycle carrier trunk and back rest, as shown.
